UNITED STATES PATENT OFFICE.

GEORGE CRANGLE, OF PHILADELPHIA, PENNSYLVANIA.

IMPROVEMENT IN ROTARY BRICK-MACHINES.

Specification forming part of Letters Patent No. 17,203, dated May 5, 1857.

To all whom it may concern:

Be it known that I, GEORGE CRANGLE, of the city of Philadelphia, in the State of Pennsylvania, have invented a new and useful Improvement in Rotary Brick-Machines; and I do hereby declare that the following is a full, clear, and exact description of the construction and operation of the same, reference being had to the accompanying drawings, making a part of this specification, in which—

Figure 1 is a vertical transverse section; Fig. 2, a top view of the cylinder, with a section of the frame which supports it; and Fig. 3 a longitudinal section of the cylinder and its shaft through the center of the same.

Like letters in the different figures indicate the same objects.

The nature of my invention consists in the peculiar construction, arrangement, and combination of a rotary cylinder open at each end and having a partition fixed transversely across the middle, and also two series of molds opening around the periphery of the same, with a stationary bed-piece fixed at each end of the frame and projecting within the cylinder, so as to serve the purpose of a bottom for each mold of the two series as they are successively passed over the same during the rotary motion of the cylinder for the purpose of reducing the cost by dispensing with the hitherto usual separate and distinct bottom for each mold of a rotary brick-machine.

Referring to the drawings, A is the cylinder, B the stationary bed-piece, and C the frame which supports the whole, and which is constructed in any suitable and substantial manner.

The cylinder A, with its partition e, is cast of iron in several pieces, the molds f f being made radially through the periphery or shell of the cylinder, so that the inner ends of one series shall be opposite to the inner ends of the divisions between the molds of the other series, and so as to be adapted for the alternating motions of two plungers (not shown in the drawings) in a well-known manner, as the said cylinder is rotated in unison therewith. The under or inner side of the shell of the cylinder, at each side of the par-

tition e, is turned true, and is parallel with the upper side of the same, and placed so as to fit accurately in contact with the middle part of the upper side of the stationary bed-piece B, the said bed-piece being fixed firmly to the frame and having its upper surface curve-formed, with a slightly shorter radius than that of the inner side of the cylinder, so as to adapt the same to fit closely to the cylinder immediately around the under parts of each mold, while the said mold is beneath the respective plunger, and at the same time allow a sufficient space, g, between the said bed-piece and cylinder to permit the pressed brick in the said mold to be so passed over the same without contact therewith after it is carried by the cylinder from off the middle of the said rest B in the direction of the arrow.

The bricks are discharged from the molds at the lower side of the cylinder upon a carrying-band in the usual manner, by means of a secondary plunger, (not shown in the drawings,) which may be made to work in unison with the main plungers, which condense the clay in the molds by carrying the rods of the said secondary plungers through the vertical grooves h h in the frame, or in any other suitable manner.

Operation: Clay being placed in the hopper and alternate stopping and moving rotation given to the cylinder A in the usual well-known manner, the bed-piece B forms a bottom to the molds during the time they are under the hopper and subsequently under the plungers, and then allows the pressed brick to pass to the place of discharge without contact with the said bed-piece B, and thus bricks may be rapidly produced from untempered clay by means of this invention without a separate and distinct bottom for each mold.

The expense of constructing and keeping in repair the movable bottoms, which have heretofore been considered indispensable for the molds in cylinders of this character, is very great, and consequently any construction whereby they may be avoided must be exceedingly useful and important to the trade.

I do not claim the manner of supporting or of operating the cylinder and plungers

herein specified or described, as these have been described and used before in other cases; but

What I claim as my invention, and desire to secure by Letters Patent, is—

A cylinder, A, without movable bottoms to the molds, in combination with a bed-piece, B, fixed to the frame of the machine so as to serve the purpose of said bottoms, the said

cylinder A and bed-piece B being constructed, arranged, combined, and operated together, as and for the purpose set forth and described.

GEORGE CRANGLE.
